INVENTOR.

BY James F. Doran

Robert S. Blair ATTORNEY

UNITED STATES PATENT OFFICE

JAMES F. DORAN, OF DANBURY, CONNECTICUT

CLIPPING MACHINE

Application filed August 10, 1926. Serial No. 128,423.

This invention relates to clipping machines for use, by way of example, in clipping surfaces such as those of velour hats or the like.

5 One of the objects of the invention is to provide a clipping machine which is practical and thoroughly efficient. Another object is to provide a machine of the above nature capable of speedily and evenly clipping the nap of a velour surface or the like to a uniform length. Another object is to provide a machine of the above nature capable of producing uniformly reliable results without requiring a highly skilled operator. Another object is to provide a machine of the above nature which is compact and self-contained, which is simple in construction and which is conveniently adjustable to meet varying conditions of use. Other objects will be in part obvious or in part pointed out hereinafter.

10 25 The invention accordingly consists in the features of construction, combinations of elements, and arrangements of parts as will be exemplified in the structure to be hereinafter described and the scope of the application of 30 which will be indicated in the following claims.

In the accompanying drawing in which is shown one of the various possible embodiments of this invention,

35 Figure 1 is a side elevation of the machine;

Figure 2 is an end view of a part of the upper portion;

40 Figure 3 is a bottom plan view of the machine, certain parts being broken away;

Figure 4 shows a modified driving connection;

Figure 5 is a section taken substantially along the line 5—5 of Fig. 4;

45 Figure 6 is a section taken substantially along the line 6—6 of Fig. 3;

Figure 7 is a section taken substantially along the line 7—7 of Fig. 6;

50 Figure 8 is a section taken substantially along the line 8—8 of Fig. 6;

Figure 9 is a section taken substantially along the line 9—9 of Fig. 3, and

Figure 10 shows the machine operating upon a velour hat.

Similar reference characters refer to similar parts throughout the several views of the drawings.

Referring now to the drawing in detail, and first to Figures 1 and 2, there is shown a frame portion 10 which has projecting therefrom, at what may be termed the rear end thereof, a handle 11 by means of which the clipping machine may be moved manually over the surface to be clipped. At the front end of the frame portion 10 is what may be termed a second frame portion 12 which is connected with the frame portion 10 in a manner which will presently be described. The frame portion 12 has mounted therein a rotatable cutter or clipping cylinder 13 and, coacting with the rotatable cutter, a knife blade or bed knife 14.

The frame portion 10 has mounted upon the upper side thereof an electric motor 15 which is connected to drive the rotatable cutter 13. Preferably, the upper surface of the frame portion 10 is shaped after the fashion of a saddle 16 which receives the motor casing and wherein the motor casing is secured, for example by screws 17. By thus mounting the driving motor for the clipping cylinder directly upon the clipper frame, distinct advantages are achieved. The use of long cumbersome flexible driving shafts is avoided, such flexible driving shafts rendering a

85 machine of this nature awkward and hard to handle because of the weight of such a driving shaft and its resistance to bending. Moreover, when the drive to the clipping cylinder is transmitted from an external source by 90 means of a flexible shaft a great deal of power is lost because of the friction, and repeated twisting and bending of the shaft gives rise to a great deal of trouble from breakage. By mounting the driving motor directly upon the clipper frame, the frictional losses are avoided and it is found that a very small motor will provide ample power for driving the clipping cylinder. Because of the reduction in frictional losses, the motor may be 95 100

of such small size that its weight is not objectionable.

In clipping a surface which is rounded or otherwise not flat, it is extremely difficult and requires the exercise of great care in order 5 to clip the nap or projecting fibers to a uniform length and also to avoid digging into the body of the material being clipped, when an ordinary clipping machine is employed. 10 It is particularly difficult to clip a rounded surface whose curvature is not uniform, but changing, as in the case of a hat crown. One of the objects of this invention is to provide a clipping machine which will clip uniformly 15 and accurately without danger of injuring the material being operated upon and without requiring such explicit care, regardless of the shape or contour of the surface being clipped.

As was mentioned above, the frame of this 20 machine in the preferred embodiment includes preferably two parts, the part 10 which carries the driving motor 15 and the handle 11, and the part 12 which carries the clipping cylinder. Referring again to Figures 1 and 25 2, the bottom surface of the frame portion 10 is provided adjacent its forward end with a pair of rounded lugs 18 and 19 which support a transverse shaft or rod 20. About this shaft 20 is a sleeve 21 which, in the operation of 30 the clipping machine, is adapted to rest against the surface to be clipped. Carried by the frame portion 12 and positioned directly beneath the bed knife 14 is a plate member 22 which is adapted also to bear against the 35 surface being clipped. This plate 22 will be described more in detail later. The frame portion 12 is connected to or mounted upon the frame portion 10 so that it can move up and down relative thereto in a direction toward and away from the surface being operated upon.

The frame portion 12, carrying the cutter 13, is preferably swiveled to the frame portion 10. As shown in Figure 6, the frame portion 45 12 has a rear wall 23 to which are secured a pair of depending lugs 24 and 25, these lugs at their lower ends being swiveled upon the shaft 20, as shown in Figure 3. The two frame portions 10 and 12 are thus swiveled together to swing relative to each other about the axis of the shaft 20. The swiveling axis is thus closely adjacent to the part of the frame portion 10 which rests upon the surface being clipped.

50 The lugs 24 and 25 are secured to the wall 23 of the frame portion 12 preferably by means of screws 26 and 27 respectively and a slotted connection, as shown in Figure 9. By loosening the screws 26 and 27, the frame 55 portion 12 may be adjusted upon the frame portion 10 upwardly or downwardly to suitable position, and angularly, to bring the axis of the cutter 13 and the axis of the shaft 20 into substantial parallelism if desired.

60 Referring now to Figure 9, the clipper is

shown operating upon a curved body 28, such as a hat crown, having projecting fibers or a nap 29, clipping the nap to a uniform length. The bottom surface of the plate 22 rests against the surface 28, and the distance therebetween and the operative edge 14^a of the knife blade 14 determines the length to which the nap is clipped. The roller 21 also rests against the surface 28 being clipped. As the clipping machine is moved along, the two frame portions 10 and 12 are able to swivel about the axis of the shaft 20 to permit the two parts 21 and 22 respectively thereof to maintain engagement with the surface 28. For example, if the curvature of the surface 28 suddenly drops off as indicated at 28^a, the cutter moves downwardly about the axis 20, the plate 22 remaining constantly in engagement with the surface being clipped to regulate the length to which the fibers are cut. All 70 that is required of the operator is to move the clipping machine, by means of the handle 11, across the surface to be clipped, and careless lifting or lowering of the handle by him does not affect the operation of the machine. 80

Preferably, a spring means is employed to urge the frame portion 12, carrying the cutter 13, to swing downwardly about its swivel 20. Referring to Figure 1, a rigid arm 30 is swiveled by a pin 31 to the frame portion 12 and, extending rearwardly therefrom, is pivotally connected by a pin 32 to a lever 33. This lever 33 is swiveled upon the frame portion 10 by a pin 34. A spiral tension spring 35, hooked over a pin 36 at its forward end, 90 tends to swing the lever 33 forwardly and hence, through the arm 30, urges the frame portion 12 to swing downwardly. The force exerted by the spring 35 may be adjusted by changing the arm of force through which it 100 acts upon the lever 33, the notched slot 37 being provided in the lever 33 for this purpose.

The downward swinging of the frame portion 12 under the urge of the spring 35 is 110 limited by an adjustable stop screw 38 (Fig. 1) which may be secured to the motor casing and is adapted to be engaged by the lever 33. The upward swinging of the frame portion 12 may be limited by a set screw 39. 115

The knife blade 14 for the cutter 13 is mounted by means of screws 40 in a block 41 (Figs 6 and 8) which is carried in a recess 42 extending upwardly into the rear wall 23 of the frame portion 12. As best shown in 120 Figure 8, the block 41, and hence the knife blade 14 therewith, is held by screws 43, 44 and 45 and is adjustable thereby. The screws 43 and 45 are threaded through the wall 23 from the top, are provided with locking nuts 46 and 47 respectively and engage the upper surface of the block 41 adjacent its two ends. The center screw 44 passes loosely through the wall 23 from the top and is 125 threaded into the block 41. The block 41, 130

and hence the knife blade 14 therewith, may be raised or lowered in the frame 12 by means of the screw 44. By means of the screws 43 and 45 the block 41 and hence the knife blade 5 may be adjusted angularly so as to bring the operative edge 14^a of the knife blade into proper parallelism with the axis of rotation of the cutter. Beneath the locking nuts 48 for the screw 44 there is provided a washer 49 10 with a rounded lower surface which rests in a rounded recess about the enlarged opening through which the screw 44 passes, so that the block 41 and the screw 44 therewith may rock for angular adjustment by the screws 43 15 and 45. By manipulation of the screws 43, 44 and 45, the knife blade is adjusted into proper relationship with the cutter 13 and is thereupon securely locked in place by the locking nuts. It will be seen that these adjusting 20 screws are conveniently accessible and that a fine adjustment may be achieved.

The plate 22 beneath the knife blade 14 is preferably secured in place by screws 50 entering the block 41. This plate 22 is preferably of springy metal, and the length of the nap which the cutter leaves may be varied by springing the plate 22 downwardly and inserting between the same and the bottom of the knife 14 members 51 of any desired thickness. In this manner the clipper is readily adjusted to cut the nap to the exact length desired.

The frame portion 12 substantially encloses the clipping cylinder 13 except for the opening 35 at the bottom adjacent the knife blade 14. The clippings removed by the cutter are drawn out rearwardly through a passage 52 in the rear wall 23, the block 41 being provided with an opening 53 which registers with this passage for permitting the discharge of the clippings. The frame portion 10 is hollow and the passage 52 leads rearwardly thereinto through a neck 54 which projects rearwardly into the frame portion 10 from the rear wall 23 of the front frame portion 12. The top and bottom walls of this neck 54 are curved, their center of curvature being substantially at the axis of the shaft 20 so that, as the two frame portions 40 swivel relative to each other, the neck 54 slides in and out of the frame portion 10 without there being occasioned any opening. The handle 11 is hollow and the interior thereof communicates with the interior of the frame 10. As shown 45 in Figures 1 and 3, the end 11^a of the handle 11 is preferably threaded for the attachment of a suitable suction for carrying away the clippings. The clippings are thus disposed of in an efficient manner and cannot collect 50 within the machine so as to interfere with its operation and, moreover, the current of air keeps the clipper cool.

Considering now the mounting of the clipper cylinder 13, this is best shown in Figure 6. The cylinder or cutter is preferably

70 mounted tightly upon a shaft 55 which is supported in anti-friction bearings. At one end the shaft 55 projects outwardly through an end cap 56 secured to the frame or casing 12, and is provided with means for forming a driving connection with the motor 15, the cap 56 serving to support the bearing 57. At the other side of the machine, the shaft 55 is preferably so supported that it does not project outwardly beyond the end of the frame 12. The end of the clipping cylinder is preferably recessed about the end portion of the shaft, and the end cap 58 has a cup-shaped part 59 projecting inwardly into this recess. This cup-shaped part 59 supports the bearing 60. The outer surface of the cap 58 is preferably perfectly smooth and, as shown in Figure 3, does not project outwardly beyond the edge of the frame portion 10. With this arrangement, the end of the clipping cylinder 13 comes close to the side of the machine and it is therefore possible to clip closely up into corners which would be inaccessible if the clipping cylinder shaft extended outwardly beyond the end of the clipping cylinder. For example, in clipping a hat crown, it is possible to clip close to the brim.

90 Referring to Figures 1 and 3, the drive from the motor 15 to the clipping cylinder 13 may be accomplished by means of a belt 61 driving from a pulley 62 mounted upon the armature shaft of the motor, to a pulley 63 mounted upon the clipper cylinder shaft 55. This belt is passed over a pair of idler pulleys 64 and 65 which are mounted upon a stud shaft 66 in the frame portion 10. The axis of rotation of the idler pulleys 64 and 65 is preferably placed as closely as possible to the axis 20 about which the frame portions 10 and 12 swivel. In this manner, as the frame portions 95 swivel relative to each other, the tension of the belt 61 does not vary materially.

100 In Figures 4 and 5 there is shown a modified form of drive from the motor to the rotating cutter, the belt drive just described being displaced by a shaft and bevel gears. Mounted upon the armature shaft of the motor in place of the pulley 62 is a bevel gear 67, and mounted upon the shaft 55 of the clipping cylinder in place of the pulley 63 is a bevel gear 68. A bevel gear 69 meshes with the gear 68 and is mounted upon the end of a shaft 70 which is rotatably supported in a bracket 71. This bracket 71 is swiveled upon the hub of the cap 56, as shown in Figure 5, so that it may swing about the axis of the shaft 55. A bevel gear 72 meshes with the gear 67 and is carried in a bracket 73. The bracket 73 is similar to the bracket 71 and is swiveled to swing about the axis of the armature shaft of the motor. The gear 72 is connected by a short shaft 74, journaled in the bracket 73, to drive a hollow shaft 75. The shaft 70 projects into the hollow part 120 125 130

and is provided with a pin 76 engaging with a slot 77. The drive is thus transmitted from the armature shaft of the motor to the gear 67, the gear 72, the hollow shaft 75, the pin 76 and shaft 70, the gear 69 and the gear 68 to the shaft 55 of the clipper cylinder. As the two frame portions 10 and 12 swivel relative to each other, the two brackets 71 and 73 may swivel and the shaft 70 may slide in the hollow part 75, so that the drive is constantly transmitted without strain on the driving connections.

Referring now to Figure 10, there is shown a manner of operating this clipping machine. When a hat, such as a hat 28, is being clipped, it is ordinarily stretched over a hat block and held by the operator in one hand while the clipping machine is moved over the surface thereof with the other hand. To render the machine easy to operate and light in the hand of the operator, it is preferably suspended from above and balanced so that it may be moved without effort. A frame 80 is provided which is swiveled to swing about a vertical axis in the bracket 81 secured, for example, to a wall. The clipping machine is suspended at the outer end of this bracket by a cable 82 passing over pulleys 83 and 84 and provided with a counter weight 85. Instead of the cable 82 and the counter weight, the clipping machine may be suspended by a spring suspension 86. In this manner the weight of the clipping machine is substantially counter-balanced and the machine may be handled with the greatest ease. The spring suspension is preferable to the counter weight suspension because the inertia to be overcome is substantially less.

The cable 82 or the spring 86 is fastened to a hook 87 which is swiveled in a bracket 88 carrying a roller 89. These parts are shown more clearly in Figures 1 and 2. The roller 89 engages the bottom surface of a curved saddle 90 which is swiveled to the motor casting 15 at either side thereof. This construction provides a universal suspension for the clipping machine and permits the greatest freedom in manipulating the machine over the surface to be clipped. The machine may be moved bodily or tilted in any direction with perfect freedom, and at the same time the operator is not required to support its weight.

From the foregoing it will be seen that there is herein provided a clipping machine which accomplishes the objects of this invention, achieving advantages of distinct practical importance. By means of this machine clipping operations may be performed with speed and accuracy upon a surface of any shape. The accuracy and uniformity of the results achieved are not dependent upon the care and skill exercised by the operator. The machine is simple and compact and yet

strong and rugged to afford long-continued dependable service.

As many possible embodiments may be made of the above invention and as many changes might be made in the embodiment above set forth, it is to be understood that all matter hereinbefore set forth or shown in the accompanying drawings, it is to be interpreted as illustrative and not in a limiting sense.

I claim as my invention:

1. In a machine of the character described, in combination, a frame, a rotatable cutter mounted to rotate about an axis extending transversely of said frame, an electric motor mounted upon said frame and connected to drive said cutter, a handle by means of which said frame may be moved manually over the surface to be operated upon by said rotating cutter, and a passage extending through said handle for the removal of clippings from said cutter.

2. In a machine of the character described, in combination, a rotating cutter, means supporting said rotating cutter for movement over a surface to be clipped thereby, said supporting means having a part adapted to rest against said surface and said rotating cutter being mounted to swing about said part during its movement over the surface being clipped.

3. In a machine of the character described, in combination, a rotating cutter, and a frame-work supporting said rotating cutter for movement over a surface to be clipped, said frame-work including two parts which are pivoted together, one of which carries said rotating cutter and both of which have parts adapted to bear against the surface to be clipped.

4. In a machine of the character described, in combination, a rotating cutter, and a frame-work supporting said rotating cutter for traverse over a surface to be clipped, said frame-work including two parts which are pivoted together for relative swinging during said traverse, one of which carries said rotating cutter and the other of which has means whereby said frame-work may be given said traverse.

5. In a machine of the character described, in combination, a rotating cutter, and a frame-work supporting said rotating cutter for traverse over a surface to be clipped, said frame-work including two parts which are pivoted together for relative swinging movement during said traverse, one of which carries said rotating cutter, and a motor for driving said cutter mounted on the other of said parts.

6. In a machine of the character described, in combination, a frame including two parts pivoted together, a rotatable cutter mounted in one of said parts, and a stationary knife blade coacting with said rotating cutter, the

- said frame part carrying said cutter having a portion adjacent the operative edge of said knife blade which is adapted to bear against the surface to be clipped, and said other frame part also having a portion adapted to bear against the surface to be clipped. 5
7. In a machine of the character described, in combination, a frame including two parts, a rotatable cutter mounted in one of said frame parts, each of said frame parts having a portion adapted to bear against the surface to be clipped, and said two frame parts being pivoted together to swing relative to each other about an axis adjacent to one of said portions. 10
8. In a machine of the character described, in combination, a frame including two parts, a rotatable cutter mounted in one of said frame parts, each of said frame parts having a portion adapted to bear against the surface to be clipped, and said two frame parts being pivoted together to swing relative to each other about an axis substantially parallel to the axis of rotation of said cutter. 20
9. In a machine of the character described, in combination, a frame including two parts, a rotatable cutter mounted in one of said frame parts, each of said frame parts having a portion adapted to bear against the surface to be clipped, and said two frame parts being pivoted together to swing relative to each other, and spring means urging said frame parts to swing relative to each other. 30
10. In a machine of the character described, in combination, a frame including two parts, a rotatable cutter mounted in one of said frame parts, and a stationary knife blade coacting with said cutter, said frame part carrying said cutter having a portion adjacent the operative edge of said knife blade which is adapted to bear against the surface to be clipped, and said other frame part having a portion adapted to bear against the surface to be clipped, said two frame parts being pivoted together to swing relative to each other about an axis substantially parallel to the axis of rotation of said cutter and adjacent to one of said portions bearing against the surface to be clipped. 40
11. In a machine of the character described, in combination, a rotating cutter, and a frame supporting said rotating cutter for traverse over a surface to be clipped, said frame including two parts one of which carries said rotating cutter and both of which have parts adapted to bear against the surface to be clipped, said two frame parts being connected together so as to permit relative movement thereof during traverse in a direction toward and away from the surface to be clipped. 50
12. In a machine of the character described, in combination, a rotating cutter, and a frame supporting said rotating cutter for traverse over a surface to be clipped, said frame including two parts connected together so as to permit during traverse a movement thereof relative to each other in a direction toward and away from the surface to be clipped, each of said frame parts having a portion adapted to bear against the surface to be clipped, one thereof carrying said rotating cutter, and a motor mounted on the other of said frame parts for driving said cutter. 70
13. In a machine of the character described, in combination, a rotating cutter, a frame supporting said rotating cutter for traverse over a surface to be clipped, said frame including two parts connected together so as to permit during traverse a movement thereof relative to each other in a direction toward and away from the surface to be clipped, one of said frame parts carrying said rotating cutter and a stationary knife blade coacting with said cutter and having a portion adjacent the operative edge of said knife blade adapted to bear against the surface to be clipped, and the other of said frame parts having a portion adapted to bear against the surface to be clipped. 75
14. In a machine of the character described, in combination, a frame portion having a bottom part adapted to rest upon a surface to be clipped and having a handle at one end for manual manipulation thereof, a second frame portion at the other end of said first frame, a rotatable cutter in said second frame portion and a bed knife adapted to coact with said rotatable cutter, said second frame portion being mounted upon said first frame portion for up and down movement relative thereto. 80
15. In a machine of the character described, in combination, a frame portion having a bottom part adapted to rest upon a surface to be clipped and having a handle at one end for manual manipulation thereof, a second frame portion at the other end of said first frame, a rotatable cutter in said second frame portion and a bed knife adapted to coact with said rotatable cutter, said second frame portion being mounted upon said first frame portion for up and down movement relative thereto, and spring means urging said second frame portion downwardly relative to said first to carry said cutter toward the surface to be clipped. 90
16. In a machine of the character described, in combination, a hollow frame portion having a bottom part adapted to rest upon a surface to be clipped, a second hollow frame portion at one end of said first frame portion, a rotatable cutter mounted in said second frame portion and a bed knife adapted to coact with said cutter, said second frame portion being mounted upon said first frame portion for up and down movement relative thereto, and a passage for clippings from said second hollow frame into said first hollow frame, said first frame having means for removal of said clippings therefrom. 100

- 120
- 125
- 130

17. In a machine of the character described, in combination, a hollow frame portion having a bottom part adapted to rest upon a surface to be clipped, a second hollow frame portion at one end of said first frame portion, a rotatable cutter mounted in said second frame portion and a bed knife adapted to coat with said cutter, said second frame portion being mounted upon said first frame portion for up and down movement relative thereto, and a passage for clippings from said second hollow frame into said first hollow frame, said first frame having at the end thereof remote from said second frame a hollow handle by means of which said frame may be manipulated and through which said clippings may be removed. 70
18. In a machine of the character described, in combination, a frame portion having a bottom part adapted to rest upon a surface to be clipped, a second frame portion at one end of said first frame portion and swiveled thereto to swing thereon toward and away from the surface to be clipped, a rotating cutter mounted in said second frame portion, and spring means acting between said two frame portions and urging said second frame portion to swing toward the surface to be clipped to hold said cutter in operative relation thereto. 80
19. In a machine of the character described, in combination, a frame portion having a bottom part adapted to rest upon a surface to be clipped, a second frame portion at one end of said frame portion and swiveled thereto to swing thereon toward and away from the surface to be clipped, a rotating cutter mounted in said second frame portion, said two frame portions being hollow and having telescoping parts forming a passage for clippings from said cutter rearwardly into said first frame portion. 90
20. In a machine of the character described, in combination, a frame, a rotatable cutter mounted in said frame, an electric motor mounted upon said frame and connected to drive said cutter, means for moving said frame manually over the surface to be operated upon by said rotating cutter, and a universal suspension for supporting the weight of said frame and the parts carried thereby during said manual handling thereof, said suspension including a curved saddle and a roller engaging with said saddle. 100
21. In a machine of the character described, in combination, a rotating cutter, a stationary knife blade coacting with said cutter, a block upon which said knife blade is mounted, and means including three adjustment screws for moving said block so as to adjust said knife blade toward and away from said cutter and angularly relative to said cutter. 110
22. In a machine of the character described, in combination, a rotating cutter, a frame in which said rotating cutter is mounted adapt- 120
- ed to rest against a surface to be clipped by said cutter, and a handle for said frame for manual guiding thereof and pivotally connected thereto to permit relative swinging between said handle and said frame during the clipping operation. 125
23. In a machine of the character described, in combination, a clipping tool, a frame in which said tool is carried having a part adapted to rest against the surface to be clipped, and a handle having a part adapted to be gripped by an operator for moving said frame across the surface being clipped, said handle having a part associated therewith adapted to rest against the surface being clipped and being arranged to permit movement of said tool relative thereto in a direction toward and away from the surface being clipped during the clipping operation. 130
24. In a machine of the character described, in combination, a clipping tool, a frame in which said tool is carried adapted to rest against the surface to be clipped, and means adapted to be gripped by an operator for manually moving said frame across the surface to be clipped, said means being arranged automatically to permit the operative plane of said clipping tool to remain at a predetermined distance from said surface independently of movements of the operator's hand toward or away from said surface. 140
25. In a machine of the character described, in combination, a rotating cutter, a frame in which said cutter is mounted, means interposed between the operative plane of said cutter and the surface to be clipped to determine the length of nap left by said cutter and adapted to rest against the surface being clipped, and said frame having a part spaced from said last means adapted to rest against said surface. 150
26. In a machine of the character described, in combination, a rotating cutter, a frame in which said cutter is mounted, means interposed between the operative plane of said cutter and the surface to be clipped to determine the length of nap left by said cutter and adapted to rest against the surface being clipped, said frame having a part spaced from said last means adapted to rest against said surface, means pivotally connected to said frame for moving the same across said surface, and a motor mounted upon said frame and connected to drive said cutter. 160
27. In a clipper, in combination, a frame, a bed knife thereon having a cutting edge, a cutter rotatably mounted in said frame with its axis substantially parallel to said bed knife edge and having a plurality of blades to coat with said bed knife, said frame having a part adjacent said bed knife edge adapted to bear against the surface to be clipped, said frame and the surface to be clipped being adapted to be moved relatively in a direction transversely of the bed knife edge during the clip- 170

ping operation, a rotary electric motor mounted upon said frame with its axis spaced from the axis of said cutter, and a driving connection between the shaft of said motor and said rotary cutter.

- 5 28. In a clipper, in combination, a frame, a bed knife thereon having a cutting edge, a cutter rotatably mounted in said frame with its axis substantially parallel to said bed knife edge and having a plurality of blades to coact with said bed knife, said frame having a part adjacent said bed knife edge adapted to bear against the surface to be clipped, said frame and the surface to be clipped being adapted to 10 be moved relatively in a direction transversely of the bed knife edge during the clipping operation, a rotary electric motor mounted upon said frame and connected to drive said rotary cutter, said frame and said parts carried thereby being adapted to be manipulated manually 15 during the clipping operation and said frame having a handle to be gripped for manipulation thereof, and spring means for suspending said frame during manipulation thereof adapted to substantially counterbalance the 20 weight of said frame and of said parts carried thereby.

29. In a clipper, in combination, a frame, a bed knife thereon having a cutting edge, a cutter rotatably mounted in said frame with its axis substantially parallel to said bed knife edge and having a plurality of blades to coact with said bed knife, said frame having a part adjacent said bed knife edge adapted to bear against the surface to be clipped, said frame and the surface to be clipped being adapted to be moved relatively in a direction transversely of the bed knife edge during the 35 clipping operation, a rotary electric motor mounted upon said frame on the side thereof opposite to that which faces the surface being clipped and with its axis substantially parallel to that of said rotary cutter, and a driving connection between said motor and said cutter.

30. In a clipper, in combination, a frame, a bed knife thereon having a cutting edge, a cutter rotatably mounted in said frame with its axis substantially parallel to said bed knife edge and having a plurality of blades to coact with said bed knife, said frame having a part adjacent said bed knife edge adapted to bear against the surface to be clipped, said 40 frame and the surface to be clipped being adapted to be moved relatively in a direction transversely of the bed knife edge during the clipping operation, a shaft connected to rotate with said cutter and projecting through one side of said frame, an electric motor mounted on said frame on the side thereof opposite to that which faces the surface being clipped, the shaft of said motor projecting therefrom at said one side of said frame, and a driving connection between said projecting motor shaft and said projecting cutter shaft.

31. In a clipper, in combination, a frame, a bed knife thereon having a cutting edge, a cutter rotatably mounted in said frame with its axis substantially parallel to said bed

knife, said frame having a part adjacent said bed knife edge adapted to bear against the surface to be clipped, said frame and the surface to be clipped being adapted to be moved relatively in a direction transversely of the bed knife edge during the clipping operation, a rotary electric motor mounted upon said frame and connected to drive said rotary cutter, said frame and said parts carried thereby being adapted to be manipulated manually 70 during the clipping operation and said frame having a handle to be gripped for manipulation thereof, and spring means for suspending said frame during manipulation thereof adapted to substantially counterbalance the 75 weight of said frame and of said parts carried thereby.

32. In a clipper, in combination, a frame, a bed knife mounted on the bottom of said frame, a rotary cutter mounted in said frame above said bed knife and coacting therewith, an electric motor mounted on the top of said frame with its axis substantially parallel to that of said cutter, and a driving connection at one side of said frame between said motor 80 and said cutter.

In testimony whereof, I have signed my name to this specification this thirteenth day of July, 1926.
